UNITED STATES PATENT OFFICE.

ERNEST K. ADAMS, OF NEW YORK, N. Y.

COMPENSATING PENDULUM.

SPECIFICATION forming part of Letters Patent No. 594,865, dated November 30, 1897.

Application filed March 19, 1897. Serial No. 628,272. (No model.)

To all whom it may concern:

Be it known that I, ERNEST K. ADAMS, a citizen of the United States, residing at New York, in the county and State of New York, have 5 invented certain new and useful Improvements in Compensating Pendulums, of which the following is a specification, reference being had to the drawings accompanying and forming a part of the same.

10 The object of my invention is to provide a device for use with pendulums which shall compensate for variations in the length of the latter, due to changes of temperature, by varying the distance between the point of suspension and the center of oscillation.

15 It has heretofore been proposed to preserve uniform the effective length of a pendulum, subject to elongation and contraction under variations of temperature, both by shifting 20 the center of suspension with reference to a fixed point of support and shifting the point of support with reference to a fixed center of suspension, this being effected, among other ways, by attaching the flexible end of the 25 pendulum at a given point to the clock-frame and employing a standard of metal of high coefficient of expansion secured at one end to the clock-frame and carrying at the other a slotted stud embracing the flexible portion 30 of the pendulum and forming the center of suspension therefor, or by suspending the pendulum from the expansible standard and securing the slotted stud to the clock-frame.

35 My invention is a device of this general character, but it is an improvement on those heretofore made mainly in the following particulars: In the previous devices of this character either the center of suspension or the point of support for the pendulum occupied 40 a position intermediate to the ends of the expansible standard and independent thereof, and as a consequence the expansion and contraction of the clock-frame or supports for the standard itself played a part in 45 determining the effective length of the pendulum, and thus introduced an element of error which there was no means of correcting or providing against. This objection I avoid by arranging the two points mentioned at opposite ends of the expansible standard, so 50 that they will always exactly accord in position with the ends of the standard. To suc-

cessfully accomplish this, I employ an expansible standard of hard rubber in lieu of the metal heretofore employed, and I make 55 the standard in cylindrical form and provide means for adjusting its length whereby its approximate length may not only be predetermined with greater accuracy, but its exact 60 length readily secured.

Referring now to the drawings, which illustrate the principle of construction and mode of operation of my invention in two of the many forms of pendulum to which it is applicable, Figure 1 is a top plan view, and Fig. 2 a 65 vertical section, of an oscillating pendulum. Figs. 3 and 4 are similar views, respectively, of a torsional pendulum; and Figs. 5 and 6, plan and sectional views, respectively, of a slotted plate through which the flexible portion 70 of the pendulum passes.

F designates the supporting plate or frame which carries the pendulum and which is formed or provided with a lateral bracket or platform F'. Mounted on the latter is the 75 expansible standard, which is composed of vulcanite or hard rubber and preferably adjustable in length by being made in three parts—a main cylinder R², a shorter cylindrical section R', and a coupling-sleeve R³. 80 The section R' and sleeve R³ are threaded, the former being secured against rotation by pins T set in the part R² and entering holes in the part R', so that by turning the sleeve R³ to the right or the left varies the total height of 85 the standard.

The pendulum is of any usual construction, but comprises a flexible strap or band S of somewhat greater length than the expansible standard. The remaining parts may be of 90 any ordinary construction, that shown in Fig. 2 consisting of a wooden rod B and a bob B'. The upper end of the strap S is suspended from a cross-bar P, resting in notches in the top of the expansible cylinder or standard, 95 and the strap passes through a slot in a plate D, secured to the lower end of the cylinder or to the platform to which the latter is fixed, and at its end.

The length or height of the expansible cylinder is calculated with reference to the predetermined or calculable rate of expansion and contraction of the pendulum by a well-understood formula, the coefficient of expansion 100

sion of the material comprising the cylinder being known, so that variations in length of the pendulum will be compensated for by the correspondingly greater variations in the height 5 of the cylinder and the effective length of the pendulum maintained uniform by the raising or lowering of its point of support. A similar effect will be secured in the case of a torsional pendulum, such as shown in Figs. 3 and 4, by 10 forming the opening in the plate D and that portion of the wire S' which passes through it in such manner that the latter is prevented from twisting at that point.

By making the expansible standard in the 15 form of a cylinder it is possible to calculate in advance and to a nicety the length required, while the exact alinement of the point of support and center of suspension are much more nearly preserved than by other forms.

20 The two forms of pendulum shown—viz., the oscillating and torsional—are evidently equivalents for the purposes of this case, although the same descriptive terms used in the claims may not strictly apply to both. I may 25 also apply the principle of my invention to other forms of pendulum, and I may vary the construction of the parts shown in many ways. For example, in lieu of the slotted or perforated plate D, I may employ any device which 30 performs the same office.

Having now described my invention, what I claim is—

1. The combination with a pendulum, of a support therefor consisting of a standard composed of a material having a coefficient of expansion higher than that of the pendulum, and a device constituting a center of suspen- 35

sion secured at one end of the standard, the pendulum being supported from a point at the opposite end of the standard and passing 40 through the center of suspension, whereby the effective length of the pendulum will be maintained uniform by the expansion and contraction of the standard and consequent variation of the distance between the point 45 of support and center of suspension, as set forth.

2. The combination with a pendulum, of a cylinder composed of a material having a coefficient of expansion higher than that of the 50 pendulum, a support at one end of the cylinder to which the pendulum is attached, and a device, such as a slotted plate, which forms a center of suspension at the opposite end of the cylinder and through which the pendu- 55 lum passes.

3. The combination with a pendulum, of a cylinder of hard rubber, a support at one end of the cylinder to which the pendulum is attached, and a slotted plate at the other which 60 forms a center of suspension through which the pendulum passes.

4. The combination with a pendulum of a support composed of a cylinder of highly-expansible material, the pendulum being supported at one end of said cylinder and passing through a contracted opening at the other, the said cylinder being formed in sections adjustable with reference to each other, whereby its length or height may be varied, as set forth. 65 70
